(57) **CLAIM**

The ornamental design for a pair of elongated sandal soles, as shown and described.

DESCRIPTION

FIG. 1 is a top perspective view of a pair of elongated sandal soles with the right sandal sole removed for clarity of disclosure;

FIG. 2 is a top view shown in a used condition thereof;

FIG. 3 is a top view thereof;

FIG. 4 is a bottom view thereof;

FIG. 5 is a side view thereof; and,

FIG. 6 is a top perspective view of a pair of elongated sandal soles.

The features shown in broken lines in the various Figures are for illustrating environmental matter and human structure, and form no part of the claimed design.
